IMPROVEMENT IN WICK INSERTER FOR LAMPS.

WILLIAM Y. A. BOARDMAN, OF NEW HAVEN, CONNECTICUT.

Letters Patent No. 60,130, dated December 4, 1866.

SPECIFICATION.

TO ALL WHOM IT MAY CONCERN:

Be it known that I, WILLIAM Y. A. BOARDMAN, of New Haven, in the county of New Haven, and State of Connecticut, have invented a new device for Inserting Wicks in Lamps; and I do hereby declare the following, when taken in connection with the accompanying drawings, and the letters of reference marked thereon, to be a full, clear, and exact description of the same, and which said drawings constitute part of this specification, and represent, in—

Figure 1, a side view.

Figure 2, an edge view.

Figure 3, a section on line xx ; and, in

Figure 4, its operation.

My invention relates to an improvement to facilitate the insertion of the wick through the tubes of lamps, designed more particularly for kerosene lamps, but equally applicable to all lamps using a flat or similar wick. The inconveniences which attend the introduction of the wick into the tube are too well known to require specification; by my invention these difficulties are entirely overcome, and in order that others may be enabled to construct and use my improvement, I will proceed to describe the same, as illustrated in the accompanying drawings.

From a piece of sheet steel or other suitable metal I cut to the form shown in fig. 1, of the proper width to permit it to pass through the tube of the lamp, the lower end pierced as at A, or other device by which the instrument may be hung up or otherwise disposed of when not in use. The upper end I slit into five parts, (more or less,) a and d , two of the parts corresponding to the feed-wheels of the wick-tube; two of these parts, d , I bend outward in one direction, the other parts, a , in the opposite direction; that is, alternate parts in the same direction. These several parts, or fingers, as they may be called, are pointed, and the points turned inward, as seen in fig. 2, and thus formed, possess considerable amount of elasticity. In order to strengthen the fingers, and the body or handle, I corrugate the body, as denoted in fig. 3, the corrugation extending up through the corresponding fingers, d , the other fingers curved in like manner. If formed of steel the fingers should be tempered, if of other material it should be treated with a like object, according to its nature; my instrument is then ready for use, which is as seen in fig. 4. When it is desired to insert the wick in the tube, pass the lower end or handle of the instrument through the tube, either from the upper end down, or *vice versa*, and before the points are closed by passing into the tube, as denoted in fig. 4, place the end of the wick within the grasp of the several fingers, then draw the instrument, with the wick securely held, through the tube, as seen in fig. 4, taking care in the insertion of the instrument that the two spaces correspond to the two wheels in the tube. By this arrangement not the slightest difficulty is found in the insertion of the wick.

Having therefore thus fully described my invention, what I claim as new and useful, and desire to secure by Letters Patent, is—

The herein-described instrument for inserting wicks in lamp-tubes as a new article of manufacture.

WM. Y. A. BOARDMAN.
